STIRRING ASSEMBLY

John W. Zabriskie, Kingsport, Tenn., assignor to
 Eastman Kodak Company, Rochester, N. Y., a
 corporation of New Jersey

Application November 26, 1941, Serial No. 420,593

4 Claims. (Cl. 287—126)

This invention relates to adjustable couplings, and more particularly to couplings for stirring assemblies, one end of which is unsupported. Such structures are in common use in closed tanks, wherein the stirrer or agitator is located at the lower end of a shaft and has no step-bearing. This type of stirring mechanism, unless very accurately aligned, is likely to set up a wobble or weaving motion of the entire assembly, with destructive results.

The type of stirring device in which no step-bearing or bottom guide is provided is commonly adopted when corrosive mixtures are being worked, or in handling materials which would affect or be affected by metals. Under such conditions, it is desirable to construct all of the immersed portion of the agitator of a relatively inert material that is not readily affected if at all, by the mixture and wood is one such relatively inert material which is well adapted for this type of service, because it is cheap and readily replaceable. However, it has been difficult heretofore to attach such an agitator or stirrer with an unguided lower end to the driving mechanism or head shaft and readily obtain an accurate alignment of both parts. The present invention is directed to the elimination of this difficulty, and to an improved construction whereby a stirrer may be easily and quickly aligned with its supporting coupling, particularly when being replaced.

As most stirring devices have vertical shafts, the specific example of the invention shown and described herewith is designed for use in a vertical position. However, the invention should not be visualized as limited to the exact form and position of the members shown.

In the drawing, wherein like reference numerals designate like parts throughout,

Fig. 1 is an exterior elevation of a stirring assembly embodying this invention, only a fragmentary portion of the stirrer being shown;

Fig. 2 is a top view of Fig. 1;

Fig. 3 is a vertical central section of the assembly shown in Fig. 1, on an enlarged scale;

Fig. 4 is a horizontal section-plan on line 4—4 of Fig. 3, and

Fig. 5 is a perspective view of the upper end of the agitator or stirrer.

The stirring assembly comprises a socket member 10 and a hub member 11, these parts having mating flanges 12 and 13 respectively. A driving shaft 14 has a reduced end 15 that enters a central bore in the hub member 11 and may be held therein by a key 16 and a setscrew 17. Near the lower end of the portion 15 is an annular groove

wherein a split ring 18 is seated so that when the socket member 10 and hub member 11 are drawn tightly together by bolts 19 the ring 18 will be enclosed in a recess that is partly in each of said members 10 and 11, thereby retaining the assembly on the shaft 14.

A prime alignment of the stirrer member is obtained by relative angular alignment between the socket member 10 and hub member 11. For this purpose the top face of the flange 12 and bottom face of the flange 13 are machined at a slight angle, that is, said faces are not perpendicular to but make an oblique angle with the axis of the shaft 14. The bolts 19 pass through close fitting holes in the flange 12, but flange 13 is provided with arcuate slots 20 (Fig. 2) so that the socket member 10 and hub member 11 may be rotated with respect to each other through several degrees. When members 10 and 11 are so relatively rotated, the nuts 19' on bolts 19 being loosened, the bevel of the flange faces above mentioned causes the axis of the members 10 and 11 to diverge to an increasing extent, this being one of the arrangements for obtaining required shaft alignment.

The socket member 10 is substantially hollow and has at its lower end an open square socket 21 and above and coextensive therewith a tapered round socket 22. These sockets 21 and 22 are adapted to receive the upper end of a stirrer 23 of wood, plastic, or other non-corrosive material. Said stirrer 23 is preferably square and has a conical or round and tapered end 24, see Fig. 5. Said conical or tapered end 24 is slightly larger than but fits into the socket 22 of the socket member 10 while the upper portion of the square stirrer 23 fits into socket 21.

The stirrer 23 is connected to the socket member 10 by means of nuts 25' and 26' threaded respectively onto drawbolts 25 and 26 which extend through laterally-projecting lugs 27 of the socket member 10. Threaded pins 28 and 29, respectively, pass entirely through the stirrer 23 at right angles to and axially spaced from each other and extend through eyelets in the lower ends of bolts 25 and 26. Spacers 30 are interposed between the eyelets of drawbolts 25 and 26 and the stirrer 23 to insure approximate alignment of said bolts 25 and 26 with the lugs 27. Nuts 28' and 29' are threaded onto the ends of said pins 28 and 29, respectively.

As the bolts 25 and 26 are arranged in quadrature, it is apparent that if any one of the nuts 25' or 26' is turned down or tightened, the enlarged conical end 24 will change its position

with the conical socket 22 and the stirrer 23 will be drawn toward that side. Conversely, if a nut 25' or 26' is loosened, decreasing the tension on the associated drawbolt 25 or 26 then the tension of the other bolts 25 and 26 can shift said enlarged conical end 24 in the socket 22 and draw the stirrer 23 in the opposite direction. It is thus possible to secure a very accurate alignment of the stirrer 23 with the driving shaft 14, and when once set up the alignment will not change because the enlarged conical end 24 of the stirrer 23 is wedged into socket 22.

By means of the beveled meeting faces of flanges 12 and 13 and the slots 20 a semi-adjustment of the stirrer 23 is obtained, and final accurate alignment is made by carefully tightening the nuts 25' and 26' on bolts 25 and 26 as required, until the lower unsupported end of the stirrer 23 runs concentric with the driving shaft 14 and does not describe a circle about the center. The beveled flange connection alone is not sufficient to provide for fine adjustment and alignment.

While constructions employing a pair of mating beveled flanges have been used for aligning separate sections of pipes and the like, they afford only an approximate alignment of the parts, not suited for use with a revolving shaft. The separate draw bolts or equivalent adjustable means shown herewith permit an exceedingly close and accurate alignment which will remain so under stress in use.

Having now particularly described my invention, what I desire to secure by Letters Patent of the United States and what I claim is:

1. A stirring assembly comprising a hub member mounted for rotation about an axis, a socket member provided with a conical recess, complementary surfaces on said hub and socket members at an oblique angle to said axis, adjustable connecting means between said hub and socket members for permitting relative rotational adjustment therebetween, a stirrer having a conical end adapted to fit into said recess in the socket member, and a plurality of longitudinally adjustable connections between said stirrer and said socket member and selectively adjustable to move the conical end of said stirrer within and with

respect to said conical recess to center the axis of rotation of said stirrer.

2. A stirring assembly comprising a socket member provided with a recess having a conical portion and a square portion, a square stirrer fitting into the square portion of said recess and having one end formed conically and larger than the conical portion of said recess, and a plurality of longitudinally adjustable connections between 10 said stirrer and said socket member and individually adjustable to vary the alignment of the axis of rotation of said stirrer with respect to said socket member.

3. A stirring assembly comprising a socket member mounted for rotation about an axis, provided with peripherally spaced longitudinal openings, and provided with a recess having an upper conical portion and a lower square portion, a square stirrer fitting into the square portion of 20 said recess and having one end formed conically and larger than the conical portion of said recess, a pair of cross pins extending transversely through said stirrer and axially spaced from each other, a plurality of drawbolts connected at one 25 end to the ends of said cross pins and extending into the openings in said socket member, and means for individually varying the tension on said drawbolts to vary the alignment of the axis of rotation of said stirrer with respect to said socket member.

4. A stirring assembly comprising a socket member mounted for rotation about an axis, provided with peripherally spaced longitudinal openings, and provided with a recess having an upper conical portion and a lower square portion, a square stirrer fitting into the square portion of 35 said recess and having one end formed conically and larger than the conical portion of said recess, a pair of cross pins extending transversely through said stirrer and axially spaced from each other, a plurality of drawbolts connected at one 40 end to ends of said cross pins and having their other ends threaded and extending through the openings in said socket member, and nut members threaded onto the ends of said drawbolts and bearing on said socket member.

JOHN W. ZABRISKIE.
